[57] ABSTRACT

[21] Appl. No.: 248,816

The presence of beta hemolytic streptococci in a test culture is rapidly ascertained by inoculating a solid nutrient medium such as blood agar with the test culture, wherein the medium contains a ribonucleic acid preparation consisting essentially of ribonucleic acid core, and observing the medium for appearance of markedly enhanced hemocytic characteristics of the streptococci.

TEST FOR HEMOLYTIC STREPTOCOCCI AND
TEST MEDIA THEREFOR

BACKGROUND OF THE INVENTION

This invention relates to a rapid and markedly enhanced test for the presence of hemolytic streptococci and to test media therefor. More particularly, the invention concerns a diagnostic test for beta hemolytic streptococci which will yield presumptive results usually within less than eight hours and which is adaptable for use by relatively unskilled personnel in hospitals, clinics, physicians offices and the like.

Lancefield Group A beta hemolytic streptococci are associated with a wide variety of ailments in mammals, including such human ailments as respiratory infections of various kinds. These bacteria are dangerous pathogens and the early determination of their presence is therefore important for treatment of a patient afflicted with ailments attributable to these bacteria. For example, if their presence can quickly be determined, a medicinal specific to their control may be administered before an illness reaches a serious level. Heretofore, a presumptive diagnostic test for these bacteria has required at least 18 to 24 hours, thus permitting the proliferation of the bacteria while the diagnostic test is being completed, or promoting the interim use of medicinals which are not necessarily protective against the streptococci or which may have side effects which would have been avoidable if the diagnosis had been completed earlier.

The term "hemolytic" or like term means the rupture or lysis of mammalian red blood cells or corpuscles (erythrocytes) whereby the hemoglobin is released. This occurrence is observed in the form of transparent zones ("lakes") at the original site of the cells. One of the three major groups of Streptococcus bacteria, the so-called "pyogenic" (pus-forming) group, includes highly pathogenic bacteria which have the property of inducing hemolysis, and therefore their presence can be determined by observing a suspect culture for this occurrence. Under controlled conditions, the two subgroups of hemolytic streptococci can be distinguished: the *S. pyogenes* group and the *S. viridans* group, also known as beta hemolytic streptococci and alpha hemolytic streptococci, respectively.

In the case of hemolysis induced by beta-hemolytic streptococci, the zones of hemolysis appear around the streptococci colonies, and when the test medium is blood agar, the zones are entirely clear, almost colorless (grey cast), and free from intact red blood cells. In the case of alpha hemolytic streptococci, the nearly colorless zone of hemolysis is also observed, but in addition, there is a zone of discolored but intact red blood cells close in and around the streptococcal colonies. When blood agar is the test medium, the red blood cells in the region of alpha hemolytic streptococci have a green or brownish green color. When deep colonies of streptococci in blood agar plates show no visible change in the blood cells surrounding the colony, the bacteria are said to be of the gamma or non-hemolytic type.

Since it has been determined that the Group A beta hemolytic streptococci are pathogens in the great majority of illnesses known to result from the presence of streptococci in humans, it is apparent that a rapid diagnostic test for the presence of these bacteria will have far reaching benefits for improved health.

OBJECTS AND SUMMARY

Accordingly, an object of the invention is to provide a new and improved test for beta hemolytic streptococci having the characteristics of specificity of reaction, increased hemolytic reactions, simplicity (permitting use by non-specialized health personnel), and rapid reading time.

Still another object is to provide a new and improved diagnostic test for hemolytic streptococci having a reading time usually of 8 hours or less, and test media therefor.

Still another object is to provide a new and improved rapid diagnostic test for beta hemolytic streptococci, and test media therefor, which can be used at a wide variety of locations including hospitals, clinics and physicians offices.

These and other objects, features and advantages of the invention will become apparent from the specification which follows.

In summary outline, it has been discovered that the combination of a solid nutrient (growth) medium for hemolytic streptococci and a ribonucleic acid preparation consisting essentially of ribonucleic acid core material, markedly increases the rate of hemolysis when hemolytic streptococci are present so that test results can be read at least presumptively usually within 8 hours. Since the preferred form of the test medium of the invention (blood agar plate) is inexpensive and easily obtainable, and since relatively little experience is necessary to read the test results, the invention provides a procedure which can be effectively utilized at health centers visited by the patients. As a consequence, the usual procedure of taking a test culture from a patient, transporting it to another location for the diagnosis, and then reporting the test results to the health officer and patient, can be abrogated with very substantial savings in time and expense. The invention therefore provides a significant contribution to the alleviation of illnesses associated with Group A beta hemolytic streptococci.

The invention accordingly comprises the several steps and the relation of one or more of such steps with respect to each of the others, the apparatus embodying features of construction, combination and arrangement of parts which are adapted to effect such steps, and the article which possesses the characteristics, properties and relation of elements, all as exemplified in the detailed disclosure hereinafter set forth, and the scope of the invention will be indicated in the claims.

DETAILED DESCRIPTION

The solid nutrient medium is any medium which provides a growth environment for hemolytic streptococci and which will permit the observation of typical hemolysis if it occurs. The most extensive experience to date has been with agar formulated in known ways in admixture with a nutrient material such as a beef broth infusion. Agar base media, particularly when used with Petri plates, are transparent and colorless, are not digested or liquified by most bacteria, melt only at boiling temperature, and once melted, do not set again until body temperature has been reached. The agar generally is present in the nutrient material in amounts of about 1.5 to about 3.0 percent by weight. Both natural and synthetic nutrient materials may be used, including meat (such as beef) or vegetable broths, whether of the

extract or infusion types. Peptones are also common nutrients. The nutrient medium may also be in dehydrated form and may contain synthetic nutrient substances such as certain carbohydrates, amino acids, phosphates and fermentates.

In place of agar, solid surfaces may be used to provide the solid medium. Among these may be mentioned highly porous membranes of certain plastic materials including cellulose acetate, colodian or the like. In one such technique, a membrane is mounted on a perforated plate and supported in a funnel-shaped vessel. The membrane then acts as a sieve to filter the micro-organisms from a test fluid or from a dilute broth culture of the test fluid. After fluid has passed through the membrane, the organism is deposited on the surface and the membrane is removed from the vessel and placed on a disk or pad or blotting paper (which may be saturated with a nutrient solution if the test solution did not contain a nutrient). The nutrients then diffuse through the membrane and cause growth of colonies on the surface in the same manner as in agar.

The foregoing and other culturing techniques employing solid nutrient media are well known, such as described in Frobisher, *Fundamentals of Microbiology*, 8th Ed., W. B. Saunders Co. (1968), pages 38-44, and the invention includes the use of such other media and the obvious variants thereof.

To the nutrient medium is added defibrinated sheep red blood cells in the amount generally of about 3 to 5 percent by volume. While almost any type of mammalian red blood cells may be used, such as defibrinated horse, rabbit or sheep blood cells, human blood cells normally should not be used where the diagnosis requires distinction to be made between beta and alpha hemolytic streptococci, because alpha hemolytic streptococci, which produce alpha hemolysis on sheep blood, frequently will appear to be beta hemolytic on human blood plates, thus confusing the diagnosis. Sheep red blood cells are preferred because they contain an inhibitor for *Hemophilus hemolyticus*. This organism is often difficult to distinguish from beta hemolytic streptococci by gross inspection.

Also present in the solid nutrient medium is a yeast extract known as "ribonucleic core" (hereinafter "RNA core"). This material is the lyophilized limit polynucleotide which remains after exhaustive enzymatic hydrolysis of yeast ribonucleic acid (RNA) and removal of digestion products by dialysis. This material is commercially available and its preparation is described by R. J. Hilmo, *J. Biol. Chem.* 235, 2117 (1960). RNA core is aptly named since it is the limit nucleotide rather than a crude yeast nucleotide extract or a purified extract which is available in varying degrees of purity.

In a standard mode of preparation of the solid nutrient medium of the invention, a conventional blood agar base material (pre-prepared to contain the required amount of beef nutrient infusion or suitable peptones) is heated to boiling to dissolve the agar, and the solution is adjusted to pH 7.5 by the addition of a suitable buffering agent. The solution is then sterilized in an autoclave and cooled to about 50°-60° C. RNA core is separately dissolved in a minimal amount of distilled water and added to the cooled solution. The mixture is allowed to cool to 45°-50° C. before adding 5 percent by volume defibrinated sheep red blood cells. The mixture is then poured into sterile plates and allowed to so-

lidify and is then ready for inoculation with a test culture. The thus-prepared blood agar plates may also be stored under refrigeration for several weeks for use when and where desired.

5 The concentration of RNA core will depend somewhat upon the type of solid nutrient medium and the relative proportions of ingredients in the medium. For the standard blood agar plate, it has been determined that about 10-25 mg. percent (per 100 cc. of total nutrient medium prior to solidification) provides the best results. Amounts of RNA core in excess of this do not improve the readability, and it has been found that amounts in the range of about 200 mg. percent actually inhibit the hemolysis.

10 15 The solid nutrient medium containing the RNA core and red blood cells may be inoculated with a test culture and observed for hemolysis using any of the techniques well known in the art. For example, it is conventional to first streak the surface of the agar plate parallel to a crayon line which is marked on the bottom of the plate so as to divide the plate in half. Sub-surface stabs with test inoculum are also made in the medium, preferably along a line perpendicular to the crayon line.

20 25 The inoculation of the medium with the test culture can follow the addition of the RNA core to the medium or the RNA core material may be added after the inoculation with the test culture, for example as a solution of RNA core in distilled water, which solution is "dropped" into the medium with an eye dropper, for example. Also, porous membranes such as filter paper disks may be impregnated with the RNA core material and these used in place of the RNA core solution.

30 35 Following inoculation with the test culture and RNA core material, the plates normally are inverted and incubated at 37°C. If beta hemolytic streptococci are present, hemolysis will be observed in the medium usually within 8 hours and often much earlier in the area of the sub-surface stabs. The hemolysis will be clearly evident and little experience is required to discern it.

40 45 Many variations are possible on the foregoing techniques and are described in the literature relating to solid nutrient medium culturing techniques, for example, Frobisher, *supra.*, pages 423-424; and P. F. Frank and M. L. Levinson, "A Laboratory Manual of Bacteriological and Serological Procedures Used In The Identification of Beta Hemolytic Streptococci", Research Project MR 005.09-1300.1, Bureau of Medicine and Surgery, Navy Department, Washington, D. C. (January, 1966 Revised), pages 7-14.

50 55 The mechanism whereby the hemolysis is markedly enhanced quantitatively and increased in rate by the solid growth medium containing the RNA core material is not fully understood but it may be related in some manner to the enhancement of production of the hemolytic toxin streptolysin S. This toxin has been implicated as the cause of hemolysis of red blood cells and it is known that the presence of ribonucleic acid extracts of yeast favor its production. However, studies of 60 65 the relationship between streptolysin S. production and yeast nucleic acid have been limited to liquid, non-growth (resting cell) media containing crude yeast nucleic acid, as in Bernheimer, "Formation of a Bacterial Toxin (Streptolysin S) By Resting Cells," *The Journal of Experimental Medicine*, 90, No. 5, pages 373-392 (1949), and to the use of RNA core as in U.S. Pat. Nos. 3,477,914 and 3,627,644 to Okamoto et al.

Despite this knowledge, so far as is known, no studies have been made of minimum times for hemolysis and the use of the reaction to ascertain the presence of hemolytic streptococci in a test culture. Moreover, although certain additives have been reported to enhance streptolysin S. production in non-growth liquid media (additives such as glucosamine hydrochloride, maltose, dextrose, cysteine hydrochloride, gibberellic acid, and thiamine hydrochloride), these additives have failed to enhance hemolytic activity in solid nutrient media. Therefore, it appears that the degree of hemolysis and the increased rate of hemolysis is not necessarily caused by increased streptolysin S. production, and it was totally unexpected that the use of a solid growth medium, in combination with RNA core material, would give the significant improvements observed in the media of the invention.

The following examples are intended as further illustration of the invention but are not necessarily limiting thereof, except as set forth in the claims. All parts and percentages are by weight unless otherwise indicated.

EXAMPLE 1

To a dehydrated blood agar base medium having a beef nutrient confined therein, available from Baltimore Biological Laboratories as Code No. 01-127, was added an amount of a buffering solution sufficient to adjust the pH to 7.5. The resulting agar medium was dissolved and sterilized. After cooling to 50°-60°C., the RNA core was added as a distilled water solution thereof to provide between 10-25 mg. percent of the material in the still-liquid medium. The RNA core was obtained from the Worthington Biochemical Corporation, Catalog No. 3472. Then 5 percent by volume of defibrinated sheep red blood cells was added to the medium which had cooled to 40°-42°C. The thus-prepared agar nutrient medium as poured into Petri plates, 17-20 ml. per plate, and permitted to solidify. The test plates (and identical plates but without the RNA core, as controls) were streaked with swabs containing known beta hemolytic cultures maintained in Stuarts Transport Medium. Sub-surface stabs were also made in the inoculated medium with a sterile platinum loop, generally following the procedures described in Frank and Levinson, "A Laboratory Manual of Bacteriological and Serological Procedures Used In The Identification Of Beta Hemolytic Streptococci," supra,

Observations of six such sets of plates after 3½ hours and after 6½ hours incubation at 37°C. are reported in Table I below, where "+ stab" indicates positive identification in a sub-surface area of the plates and the numeral indicates the relative widths of the hemolytic zones. In each instance, the control plates displayed no hemolysis before 12 hours of incubation whereas most of those plates containing the RNA core exhibited easily visible hemolysis in the subsurface areas after 3½ hours, which hemolysis rapidly increased and was observable on the surface after 6½ hours.

TABLE I

Specimen	Control Plate	3½ hrs.		6½ hrs.	
		1+ stab	—	2+ stab	—
1	Test Medium	—	—	—	—
2	Control	—	—	—	—
3	Test	+ ± stab	—	2 - 3+ stab	—

	Control	+ stab	—	1+ stab	—

6	Test	+ ± stab	2+ stab
	Control	—	—
	Test	+ ± stab	2+ stab

EXAMPLE 2

5 Control plates and test plates were prepared substantially as described in Example 1 but the RNA core material was added as a solution from an eye dropper to the agar medium after the medium had been inoculated with a known beta hemolytic streptococci culture. In 10 this series of experiments, reported in Table II below, recipe A contained 50 mg. percent RNA core, recipe B contained 100 mg. percent RNA core, and recipe C contained 150 mg. percent RNA core. The nutrient medium of each plate also contained 5 percent by volume sheep red blood cells and 0.2 g. percent maltose. The pH was adjusted to 7.5. Excellent hemolysis was observed after 6 hours with significant additional enhancement of hemolysis upon further incubation, and was essentially the same after 6 hours and 24 hours. The reference to "surface" in Table II means a zone of hemolysis on the surface of the agar.

TABLE II

Recipe	6 hours.		24 hours.
	3+ stab, 2+ surface	± stab	4+ stab, 4+ surface despite overgrowth of staphylococci
A	3+ stab, 2+ surface	± stab	2+ stab, multiple colonies with surface hemolysis
B	—	—	4+ stab, 4+ surface
C	1+ stab	—	—

EXAMPLE 3

Substantially as described in Example 1, test and control plates were prepared, inoculated with known strains of beta hemolytic streptococci, and observed for hemolysis. In these experiments, reported in Table III below, the concentration of RNA core was varied between 10 and 50 mg. percent. As compared with Examples 1 and 2, it can be seen that the best results were obtained when the RNA core was present in the range of this Example.

TABLE III

55

In view of the foregoing description it will be apparent that the invention is not limited to the specific details set forth therein for the purposes of illustration, and that various other modifications are equivalent for the stated and illustrated functions without departing from the spirit and scope of the invention.

What is claimed is:

1. An improved diagnostic test for beta hemolytic streptococci, characterized by marked enhancement of hemolysis and increased rate of hemolysis, which comprises inoculating a solid nutrient medium with a culture suspected of containing said streptococci, wherein

said medium contains red blood cells capable of hemolyzing in the presence of said streptococci, said medium also containing a ribonucleic acid preparation consisting essentially of ribonucleic acid core, and observing said medium for the appearance of hemolytic characteristics of said streptococci.

2. A diagnostic test as in claim 1 wherein said solid nutrient medium comprises a mixture of agar and a meat extract or infusion.

3. A diagnostic test as in claim 1 wherein said red blood cells comprise defibrinated sheep blood cells in an amount effective for inhibition of growth of *Hemophilus hemolyticus*.

4. A diagnostic test as in claim 1 wherein said solid nutrient medium comprises a mixture of agar and a meat extract or infusion, said red blood cells are present in an amount of about 3-5 percent by volume of said medium prior to solidification, and said ribonu-

cleic acid preparation is present in an amount of about 10-25 mg. percent per 100 cc. of said medium prior to solidification.

5. A diagnostic test as in claim 2 wherein said nutrient medium also contains a peptone.

6. A diagnostic test medium for beta hemolytic streptococci which comprises a mixture of: (a) mammalian red blood cells capable of hemolyzing in the presence of said streptococci; (b) a ribonucleic acid preparation consisting essentially of ribonucleic acid core; and (c) a solid nutrient medium for said streptococci.

7. The test medium of claim 6 wherein said red blood cells are defibrinated sheep red blood cells, and said solid nutrient medium is a mixture of agar and a meat extract or infusion.

8. A test medium as in claim 7 wherein the nutrient medium also contains a peptone.
